Attorney.

UNITED STATES PATENT OFFICE.

ERICH STEUDEL, OF CHICAGO, ILLINOIS.

FOLDABLE CARTON.

1,423,272.

Specification of Letters Patent. Patented July 18, 1922.

Application filed August 2, 1919. Serial No. 314,862.

To all whom it may concern:

Be it known that I, ERICH STEUDEL, a citizen of the United States, and a resident of the city of Chicago, county of Cook, and State of Illinois, have invented certain new and useful Improvements in Foldable Cartons, of which the following is a specification.

My invention relates to improvements in foldable cartons, and has for its object the provision of an improved construction of this character, capable of being made up into various forms and shapes, the present invention being an improvement over that disclosed in my prior patent, granted November 21, 1916.

The invention consists in the combinations and arrangements of parts hereinafter described and claimed.

20 The invention will be best understood by reference to the accompanying drawings forming a part of this specification, and in which,

Fig. 1 is a plan view of a carton, distended or flat.

Fig. 2 is a perspective view of a five-sided carton made from the construction.

Fig. 3 is a perspective view of a four-sided carton made from the construction.

30 Fig. 4 is a perspective view of a triangular carton made from the construction.

Fig. 5 is a perspective view of a circular carton made from the construction.

The preferred form of construction, as illustrated in the drawings, comprises a strip 6 of box board or like material, having a plurality of transverse creases 7 positioned thereon at equal distances apart, as shown, said creases being formed to cause "breaking" or corner-bending of the strip when

40 said strip is looped in one direction, so as to form rectilinear figures, as illustrated in Figs. 2, 3 and 4, and to prevent this "breaking" or corner-bending when the strip is looped in the opposite direction, so as to form a circular figure, as illustrated in Fig.

45 5. At one end the strip 6 is provided with a tongue 8, and slits 9 are provided, as shown, in each of the last three of the sections of said strip, defined by the creases 7, said slits 9 being adapted to receive and interlock with the tongue 8, as indicated. By this arrangement, the strip 6 may be bent into and se-

cured in either rectilinear form, as indicated in Figs. 2, 3 and 4, or in circular form, as indicated in Fig. 5. The slits 9 arranged in different sections of the strip 6, permit of the various adjustments thereof to form the rectilinear figures, and also permit of adjustments in the size of the circular figures. 60 In this way, the carton is adapted to a great variety of uses and to fit a large variety of objects of different shape, protecting said articles from injury in transportation. Usually the articles are wrapped in wrapping 65 paper after being surrounded by the carton, which, of course, serves to further protect the same.

While I have illustrated and described the preferred form of construction for carrying 70 my invention into effect, this is capable of variation and modification without departing from the spirit of the invention. I, therefore, do not wish to be limited to the precise details of the construction set forth, 75 but desire to avail myself of such variations and modifications as come within the scope of the appended claims.

Having described my invention, what I claim as new and desire to secure by Letters 80 Patent, is:

1. A foldable carton comprising a strip of flexible material transversely creased for bending along a plurality of lines adapted to form the corners of a carton having a desired 85 plurality of sides; a plurality of slits in a plurality of said sides; and a securing tongue at one end of said strip adapted to be selectively engaged with said slits to form a carton of various desired sizes and shapes, substantially as described.

2. A foldable carton comprising a strip of flexible material transversely creased for bending in one direction only along a plurality of lines adapted to form the corners 95 of a carton having a plurality of sides; a plurality of slits in a plurality of said sides; and a securing tongue at one end of said strip adapted to be selectively engaged with said slits to provide a carton capable of 100 change in size and shape, substantially as described.

3. A foldable carton comprising a strip of flexible material transversely creased for bending along a plurality of lines equally 105 spaced apart and adapted to form the cor-

22
ners of cartons having different numbers of sides; a plurality of slits in a number of said sides; and a securing tongue at one end of said strip adapted to be selectively engaged with said slits for forming an adjustable, shape transformable, carton.

In testimony whereof I have signed my

name to this specification in the presence of two subscribing witnesses.

ERICH STEUDEL.
